UNITED STATES PATENT OFFICE.

WILLIAM H. KREBS, OF NEW BEDFORD, MASSACHUSETTS.

DESIGN FOR A DISH.

41,027.

Specification for Design.

Patented Dec. 6, 1910.

Application filed January 19, 1909. Serial No. 473,200. Term of patent 7 years.

To all whom it may concern:

Be it known that I, WILLIAM H. KREBS, of the city of New Bedford, in the county of Bristol and State of Massachusetts, have invented and produced a new, original, and ornamental Design for a Dish, of which the following is a specification, reference being had to the accompanying drawing.

The drawing is a perspective view of the dish.

The design resides in the configuration of a dish for table use as shown in the drawing consisting of a lower dished portion A, forming the base from the center of which

rises a column B, supporting a smaller saucer portion C, having an outer surrounding rim *a*. The upper portion C is concentric with the lower portion A. A base D is formed under the dished portion, connecting it with A.

What I claim as my invention is:—

The ornamental design for a dish as shown and described.

WILLIAM H. KREBS.
